UNITED STATES PATENT OFFICE

2,531,527

GRAIN DISTRIBUTOR

Roy I. Patterson, Minneapolis, Minn.

Application August 19, 1946, Serial No. 691,619

1 Claim. (Cl. 193—23)

1

My invention relates to grain distributors, and has for its object to provide means for delivering grain from one or more grain elevator spouts to a multiplicity of outlet hoppers and bin spouts running to a corresponding number of bins, in combination with novel and highly efficient means of controlling the shift of transfer spouts from one to another of the outlet hoppers.

This application is an improvement of my application Ser. No. 634,026, filed December 10, 1945.

In that application and, more particularly in other prior art constructions, where a series of outlet hoppers were arranged to be connected with transfer spouts from the discharge of elevator leg spouts for delivering the grain to a selected one of the outlet hoppers and bins, varying degrees of difficulty have been experienced in moving the transfer spouts from one position to another and even greater difficulty in latching them in a proper delivery position and in releasing them for shifting to other delivery positions.

A substantial part of these difficulties have been satisfactorily met in the construction of my aforesaid application, wherein the grain delivery spouts were mounted to rotate within a cylindrical housing and to register with outlet hoppers circumferentially arranged about said casing.

My invention here provides novel and highly efficient means of rotating the several delivery spouts within the casing and at the same time of unlatching and stopping and latching the delivery spouts in operative position, all effected by a pull by hand on a single cord positioned at a point of convenient access by an operator.

It is a principal object of my invention, therefore, to provide a cylindrical distributor casing having concentrically arranged transfer spouts, each formed with a discharge opening facing an elongated outlet hopper opening, which is so formed that grain from one or more of said transfer pipes will go with certainty and no spilling into the outlet hopper and thence into the bin spouts, in combination with cord means which, when pulled by an operator, will simultaneously unlatch the transfer pipes to which the cord means is attached and rotate it, and when released will effect latching of the particular transfer pipe in position so that its opening or mouth will register with the opening to the outlet hopper.

It is a further object of my invention to provide, for each transfer pipe in the distributor a drum or pulley member, and to mount in connection with said drum or pulley member a

2

spring-actuated detent and to connect with the inner end of said detent a cord carried over guide rollers to a convenient position to be operated, whereby pulling on the cord will first withdraw from latching engagement with the spring-actuated detent and then will cause the drum and the transfer pipe connected therewith to be rotated until the spring-actuated detent is released, which will stop further rotation at a point to bring the opening from the transfer spout into registry with the opening to the selected outlet hopper.

It is a further object of my invention to mount the guide pulley directly upon the drum to which the several transfer spouts are secured and to carry a cord over some or all of the said guide pulleys to where the cord connects at its inner end with the inner end of a spring-actuated detent, whereby pulling on the cord will first pull out the detent and then will rotate the drum and the transfer spout supported thereby, and whereby release of the spring-actuated detent will check the rotation of the drum at a point which will bring the opening from the transfer spout into registry with the opening to the outlet hopper.

It is a further object of my invention to provide a drum and attached guide pulleys and an independent cord connected with an independent detent for each of the transfer spouts formed in the entire distributor machine.

It is a further object of my invention to number the outlet spouts from one to the highest number—say sixteen outlet spouts—to carry these numbers on the belt which, through a hand crank or prime mover power means, operates the pull cords, and to have the respective numbers correspond with the detent position for any of the outlet hoppers, so the operator, by stopping the winding operation opposite any of the numbers, or a selected one of said numbers, may correspondingly select the outlet hopper to which the grain will be delivered.

The full objects and advantages of my invention will appear in connection with the detailed description thereof, and the novel features of the invention by which the aforementioned useful, important and advantageous results are obtained will be particularly pointed out in the claim.

In the drawings illustrating an application of my invention in one of its forms:

Fig. 1 is a top plan view of my distributor as positioned for operation in an elevator.

Fig. 2 is a sectional view taken on line 2-2 of Fig. 3.

Fig. 3 is a sectional elevation view taken on line 3-3 of Fig. 1.

Fig. 3A is a side elevation view above the top plate of the upper cylinder showing the manner in which grain is fed to the distributor.

Fig. 3B is a top plan sectional view taken on line 3B-3B of Fig. 3A, with the elevator leg spout out of section.

Fig. 4 is a sectional fragmentary view taken on line 4-4 of Fig. 1.

Fig. 5 is a fragmentary sectional view taken on line 5-5 of Fig. 1.

Fig. 6 is a top plan view of the hopper for the upper transfer spout which receives the grain from an elevator leg spout.

Fig. 7 is a side elevation view of what is shown in Fig. 6.

As illustrated, a rectangular framework consisting of parallel supporting bars 10 and 11 and connected bars 12 and 13 is supported upon beams 14 and 15.

This support is effected by extending the respective ends 16 and 17 and 18 and 19 to overlie the tops of beams 14 and 15, as shown in Figs. 1 and 3. The beams 14 and 15 in turn are supported by beams or wall members 20 and 21, forming parts of the structure of the building in which the distributor is installed.

A cylindrical casing 22 is supported at its lower edge upon a rectangular frame consisting of the members 10, 11, 12 and 13, which are shown as angle irons. A top 23 closes the upper end of the cylinder 22 except for openings 24 and 25 and an air opening 26, as shown in Fig. 1.

The opening 24 is circular and at the center of the cylindrical casing 22, and is concentric with its walls. This opening 24 receives the end 27 of a hopper feed spout from hopper 119, by which the grain handled by the distributor is delivered to the vertical part 28 of an angularly disposed transfer spout 29.

Into the opening 25, Fig. 1, extends a second hopper feed 37 which connects with a hopper in all respects similar to hopper 119. The hopper feed spouts 27 and 37 are sealed into the top wall 23. This hopper is like hopper 27, excepting that it has a square opening at its lower end corresponding to the opening 25 in Fig. 1.

These hoppers 119 have an expanded end formed with upper and lower lips 120 and 121, to which are secured bifurcated members 122 and 123 which are formed with sealing slots 124 and 125, Fig. 3B. Plate 126 has its edges mounted to slide on the slots 123 and 124.

Extended therethrough and sealed to plate 126 is a leg spout 136 running from an elevator leg 127.

This arrangement takes care of any settling of the elevator or of elevator floors supporting the distributor through the beams 14 and 15 which customarily takes place in grain elevators when the bins become filled and are heavily loaded, for the plate 126 is free to slide in the sealing slots 124 and 125.

The opening 26 in top plate 23, as clearly shown in Fig. 1, at the same time opens into the annular hopper space 38 and into the space within the entire casing indicated at 128 in Fig. 3. Extending from this opening 26 is a pipe 129, Fig. 3, which connects with a pipe 130. The pipe 130 has a blower 131 therein which continually draws air through opening 26, pipe 129, and pipe 130 to discharge it through a pipe 132 outside of the system.

This arrangement insures that the dust in the system both inside and outside the grain delivery channels will be withdrawn from the distributor as the grain is fed and that the grain will go to the bins free from dust.

5 The spout 28-29 is supported by a bar 30 extending along the axial center line of spout 27 and connected at 31 to transfer spout 29. A brace member 32 connected at 33 with the vertical support 30 and at 34 with the transfer spout 29 further supports the transfer spout.

The extended end 35 of rod 30 enters a thrust bearing 36 supported in the manner hereinafter described.

The top 23 has reinforced support by transverse angles 39 and 40, Figs. 1 and 3, which angles are secured to said top 23 and extend to the outer walls of cylindrical casing 22.

Suspended from the frame made up of the angles 10, 11, 12 and 13 is a lower section made up of a series of outlet hoppers 41 and a lower cylindrical member 42. The support for this lower section is clearly indicated in Figs. 1, 2 and 5. It consists of bolts 43 extending in pairs through the several frame members 10, 11, 12 and 13 so spaced as to come between pairs of outlet hoppers 41.

30 The upper ends of the bolts go through the above noted frame members and are secured by nuts 44, as indicated in Fig. 5. The lower ends of bolts 43 go through bracket members 45, as shown in Figs. 2 and 5, which bracket members are secured to the lower cylindrical casing member 42.

Nuts 46 and 47 on either side of the supporting 35 portion 48 of bracket members 45 secure the outlet hoppers in position in a circular ring in the following manner.

At the upper edge of the outside sloping wall 49 of the hoppers 41 there is formed an offset 40 angle 50 shown in cross-section in Fig. 5. And at the top of lower wall 51 is formed a V-shaped bend 52.

The offset angle part 50 fits against the lower edge of the cylinder casing 22, being curved in an arc to adapt itself for that purpose. The V-shaped bend 52 likewise fits over the lower cylindrical member 42.

By tightening the bolts these outlet hoppers 41 are secured firmly in position. They are additionally secured by bolts running through pairs of adjacent side edges 53, Fig. 5, which bolts go through the bolt holes 54 there shown.

When the outlet hoppers are thus bolted together and pulled tight by the bolts 43 the entire 55 assemblage is held together rigidly and yet so that any outlet hopper when worn or otherwise damaged can be removed or replaced by a new one.

The thrust bearing 36, which, through the rods 30 and 32, support the transfer spout 28, 29, is mounted upon a framework made up of radial rods 55, 56, 57 and 58, which cross and are united at the center directly under the thrust bearing 36, as shown in Fig. 2.

60 Additional secant rods 61 which bridge arcs of the circumferential boundary of the lower cylinder 42 further strengthen the drum or cylinder 42, which has attached to the lower part of it a funnel hopper 62. This hopper opens at its center 63 to discharge any grain which may come down from the grain conveying chutes 27 and 37, and it also conveys away overflow grain which might spill out from the outlet hoppers 41 in the event that the hoppers become clogged. By means of piping, not shown, this overflow grain is conveyed back to the pit where the ele-

vator legs were loading to convey the grain to the distributor through their delivery leg spouts.

Cross bars 59 and 60 carry at their ends a series of pulleys 64, 65, 66 and 67, as clearly shown in Figs. 2 and 3. These arms also carry a circular drum 68. The drum 68 and the arms 59 and 60 are fast on the shaft extension 35.

About the drum 68 there is wound a cord 69 which goes over a pulley 70, Fig. 3, and is connected with a weight 71. It follows that the weight 71 constantly tends to rotate the drum 68 and at the same time to rotate the shaft 30 and the transfer spouts 28 and 29, all in a counter-clockwise direction.

From a belt member 72 which runs over a pulley 73 adapted to be operated by a hand crank 74 runs a cord 75 which is attached at 76 to the belt member 72. This cord runs over a guide pulley 60' and over the pulleys 66, 67, 64 and 65 in the order named and from pulley 65 runs over a pulley 76 which guides it in a right line direction to the end 77 of a latch bar 78.

The latch bar 78 is mounted on a bracket 79 secured to the bottom of transfer spout 29 and is impelled by a spring 80 surrounding it to project at 81 beyond the inner limits 82 of the side walls of outlet hoppers 41.

It follows that when the parts are at rest the projecting part 81 of latch 7 will be forced by the gravity pull of weight 71 to engage a side wall of outlet hopper 41.

It also follows that when the crank arm 74 is turned to put pull on belt 72 and cord 75 the first effect of doing so will be to retract latch bar 76 against the pressure of spring 80 and withdraw the projected end 81 from contact with the side wall of an outlet hopper 41, after which the pull of the cord about the spaced pulleys 64, 65, 66 and 67 will cause the assemblage, consisting of the transfer spout 28 and 29, the supporting bars 30 and 32 and the drum 68 to rotate in a clock-wise direction to shift the position of the mouth of transfer spout 29 along the circumferential line of the openings into the transfer hoppers 41.

Numbers shown at 118 on the belt 72 indicate the position of the several hoppers (16 as shown) with relation to the rotation of the parts above noted, so, when the operator releases the crank member 74 opposite any of these numbers, the spring 80 will force the latch member extension 81 into its outward position and the operation of the weight 71 will cause the extended latch bar part 81 to engage the side wall of the selected outlet hopper 41 with the result that the transfer spout 28, 29 is positioned to discharge grain from the elevator leg hopper 27 into that outlet hopper, from which it will go to a selected bin.

As indicated in Figs. 3, 6 and 7, the annular hopper 38 for receiving grain from a second elevator leg hopper 37 connects with a funnel-shaped extension 83 which rotates outside of the transfer pipes 28 and 29 and above the portion of transfer pipe 29. This funnel-shaped member is supported by a drum member 84 having flanges 85 and 86 which provide a central channel 87.

As shown in Fig. 4, a series of supporting rollers 88 are mounted on shaft bars 89 which are held to the wall of drum 22 by nuts 90 and which are supported near the roller 88 by bracket member 91. In this manner the annular hopper 38 and the parts connected therewith are mounted for free rotation about the central transfer spout 28.

The drum 84 is fast on the upper hopper cylinder 38 and supports it and the connected funnel-shaped extension spout 83 for rotation about the axial center of transfer spout 28 and elevator leg hopper 27. Upon the member 28 are mounted a series of brackets 89 which carry grooved pulleys 90, 91, 92, 93 and 94. These pulleys, as clearly shown in Fig. 6, extend outside of the circumferential limits of the cylindrical member 38.

Each of the brackets 89 is provided with an upstanding lip 95, as best shown in Fig. 3. This forms in effect a circumferential channel. About these channel sections extends a cord 96 which goes over a guide pulley 97 and a large pulley 98, Figs. 1 and 3, from which it extends downwardly to a suitably heavy weight 99 which tends to rotate the entire assemblage in a counter-clockwise direction.

A belt 100, Fig. 3, runs over a windlass pulley 101 having thereon a crank 102 and has connected at its upper end a cord 103. The cord 103 runs over a guide pulley 104 and under a second guide pulley 105 supported by a bracket 106 mounted on the upper surface of transfer spout 83, a stretch of the cord 103 extending along the surface of the cylindrical annular spout extension 38.

From under the pulley 105 the cord 103 goes along the upper surface of the transfer spout 83 to the end 107 of a stop rod 108, to which end the cord 103 is secured.

The stop rod 108 is extended for sliding movements through openings 109 and 110 in guide angles 111 and 112 secured to the top of the transfer spout 83. A spring 113 is secured at one end to the member 112 and at the other end to a lug 114 on the stop rod 108. The lower part 115 of stop rod 108 extends beyond the edges of walls of the opening 116 from the transfer spout 83, in position to engage a side wall of any outlet hopper 41 which has been selected, as indicated on the scale 117 on belt 100.

It follows that rotation of the crank arm 102 will have the effect first of drawing the stop rod 108 backward to bring the extension 115 away from the position where its lower part contacts a wall of outlet hopper 41, and then it will rotate in clockwise direction the assemblage supported by drum 84 about the axial center of casing drum 22 to present the outlet 116 of transfer spout 83 to register with the upper part of the opening 82 to any selected one of transfer hoppers 41.

It also follows that the transfer spouts 29 and 33 are capable of such movement independently to bring them to register with any selected one of the outlet hoppers 41, or to register together with any selected one of the outlet hoppers 41.

And while I have shown two of said transfer spouts so operating, it is within the scope of my invention and is contemplated under requisite conditions, to have a greater number than two transfer spouts, each capable of being independently positioned in respect to any one of the outlet hoppers 41, or all of them, and capable of being positioned to discharge simultaneously into a selected one of said outlet hoppers.

The advantages of my invention have been made to appear quite clearly in the foregoing specification. The fundamental and primary advantage resides in the fact, not only that a large number of outlet hoppers are conveniently and compactly arranged circumferentially, but that the movement of the several transfer spouts to register either singly or all together with se-

lected ones of the outlet hoppers and then to lock them in position, and to unlock them, is effected by a single simple arrangement, whereby the windlass and crank for each of the several transfer spouts employed is given a position adjacent to all their several operating means, so the entire operation of unlocking, moving each and every one or all of the transfer spouts and relocking them in position is accomplished by a single simple crank operation by an operator from one single convenient position.

A further great advantage of my invention resides in the fact that the outlet hoppers, and consequently the grain bins to which they are connected, are designated by numerals which appear on the windlass belts so the operator can select the outlet hopper to which one or more of the transfer spouts can be made to discharge and can unfailingly make certain that the grain will be delivered to the selected hopper or hoppers.

A further advantage of my invention comes from the fact that there is a wide space across the opening of the outlet spouts 41 (see Fig. 1 and dotted lines at the bottom of Fig. 2) in which the rod end 115 of the stop rod 108 can pass when an operator releases the same at the cranks 74 or 132 and that the weight then pulls the stop end 115 over to contact with a side wall of the selected outlet hopper 41, so a mis-positioning of the transfer spout to the wrong outlet hopper inlet is practically impossible.

Another advantage of my invention resides in its exceedingly compact and light construction considering the very large capacity for distribution, all of which lends itself to low cost and economical operation and upkeep.

I claim:

In combination with a grain distributor embodying a cylindrical casing having a multiplicity

of outlet hoppers secured about the extent of the cylindrical wall thereof and a rotatable transfer spout within the casing, gravity means adapted to apply force to said transfer spout to move it in one direction, means fast on the transfer spout including a rod and a spring thereon for forcing it outwardly to engage a side wall of an outlet hopper for holding the transfer spout in fixed position facing the opening into a selected outlet hopper, means connected with the transfer spout which tends to rotate the transfer spout in one direction to cause the end of the rod to be held in engagement with a side wall of a hopper, and a cord directly connected with the inner end of the rod, whereby applying force to said cord first withdraws the rod from engagement with said side wall and thereafter acts to rotate the transfer spout in the opposite direction from that of the first named rotating means, release of the force applied to said cord at any point when the rod is opposite the opening into a selected hopper acting to release the rod and to permit the first named rotating means to rotate the transfer spout until the rod engages the side wall of said newly selected hopper.

ROY I. PATTERSON.
